SANITARY SMOKING STEM FOR PIPES

Joseph Szilagyi, New York, N. Y.

Application April 19, 1933, Serial No. 666,824

8 Claims. (Cl. 131—12)

This invention relates to new and useful improvements in a sanitary smoking stem for pipes.

The invention has for an object the construction of a stem as mentioned which is characterized by 5 a novel arrangement of a hollow tube adapted to threadedly engage into a bushing mounted in the base portion of a hollow pipe stem and engaging into a substantially cup shaped member arranged with a projecting stem engaging into the 10 mouth piece of the pipe in conjunction with an arrangement to allow the passage of the smoke.

Still further the invention contemplates the construction of a smoking stem for pipes substantially as described in the previous paragraph 15 which has the function of producing cool and dry smoke.

Still further the invention contemplates the arrangement of forming the stem upon the cup-shaped member with a slot extended in from the 20 end which slot is adapted to produce a certain amount of springiness to hold the cup-shaped member in place upon the mouth piece, and furthermore which slot is adapted to engage a flattened portion upon the tube to constitute a tool 25 by which the tube may be screwed into and out of place.

Another one of the objects of this invention is the arrangement of a slot upon the inner end of the pipe mouth piece adapted to coact with the 30 slot in the stem of the cup shaped member so as to provide a passage for the smoke.

Another one of the objects of this invention is the provision of a means whereby the stem of the cup-shaped member may be mounted in various 35 positions upon the mouth piece so as to determine the size of the passage for the smoke.

Still further the invention contemplates the construction of an article as mentioned which is simple and durable and which may be manufactured and sold at a reasonable cost.

For further comprehension of the invention, and of the objects and advantages thereof, reference will be had to the following description and accompanying drawing, and to the appended 45 claims in which the various novel features of the invention are more particularly set forth.

In the accompanying drawing forming a material part of this disclosure:

50 Fig. 1 is a longitudinal vertical sectional view of a pipe provided with a smoking stem according to this invention.

Fig. 2 is a perspective view of the bushing, the tube and the cup shaped member shown in 55 Fig. 1.

Fig. 3 is a transverse vertical sectional view taken on the line 3—3 of Fig. 1.

Fig. 4 is a perspective view of the inner end of the mouth piece of the pipe.

Fig. 5 is a fragmentary horizontal sectional view taken on the line 5—5 of Fig. 4.

Fig. 6 is a similar view to Fig. 1, and shows the insertion of the tube in the pipe stem.

The sanitary smoking stem for pipes is used in conjunction with a pipe having a bowl 10 65 formed with a hollow stem 11 connected with the bowl by a passage 12. A mouth piece 13 is formed with a reduced end 14 adapted to engage into the end of the hollow stem 11 and frictionally or in any other manner maintain its position. A bushing 15 is threadedly engaged into the base of the hollow stem 11. A tube 16 is threadedly engaged into the bushing and connects with the passage 12. The front end of the tube 16 is formed with flattened sides 17 for the 70 purpose hereinafter described.

A cup-shaped member 18 engages over the tube 16 and has a rear stem 19 engaging into the inner end of the mouth piece 13. The rear stem 19 is formed with a slot 20 extended in from its 80 end and adapted to align with small slots 21 extended in from the end of the reduced portion of the mouth piece 13. The slots 21 extend substantially half of the length of the reduced portion of the mouth piece as clearly shown in Fig. 85 4. It is pointed out that the smoke may travel from the interior of the hollow stem into the slots 21 through the edges upon the end of the reduced portion and then through the slot 20 in the stem 19 and then through the mouth 90 piece 13.

A means is provided for holding the stem 19 in various longitudinal positions within the end of the mouth piece so as to vary the size of the passage for the smoke. If the stem is in a position 95 illustrated in Fig. 1 then the smoke may pass directly into the end of the slot 20 in addition to passing through the slots 21 and then into the slot 20. The base portion of the slot 20 is formed of substantially V-shape so that its 100 area increases gradually and so better controls the size of the passage for the smoke as the stem is adjusted upon the mouth piece.

The means for holding the stem in various 105 positions comprises a projection 24 upon the end of the stem, on one side thereof adapted to engage into a longitudinal groove 25 formed upon the inner wall of the stem 13. This groove is formed with several transverse branches 26 so that when the stem is engaged to certain posi- 110

tions it may be rotated to cause the projection 24 to engage into one of the branches 26 and so lock the stem in the desired position. The branches 26 are so arranged that when the projection 24 is engaged into any one of them, then the slot 20 simultaneously aligns with the slots 21.

The slot 20 and the stem 19 has a still further function, namely that of a tool wherein the stem 19 may be engaged over the flattened side 17 of the tube 16, to rotate the tube manually so that it may be engaged into or removed from the bushing 15.

The operation of the device is as follows: 15 When a smoker draws upon the mouth piece 13 the smoke will be drawn in through the passage 12 and then through the tube 16 into the cup-shaped member 18. The smoke then moves backwards to the edge of the cup-shaped member and 20 around the outside of the cup-shaped member and through the slots 21, the slot 20 and the passage in the mouth piece. The path through which the smoke must go, serves to dry the smoke and produce a cool smoke.

25 It will be recognized that the juices from the tobacco cannot very readily be drawn through the mouth piece with the arrangement disclosed. Because of the exceptional path which the smoke must take it becomes cooled during its travel. 30 The pipe may be cleaned by separating the mouth piece 13 from the stem, removing the cup-shaped member 18, using the stem portion 19 as a tool to remove the tube 16 and then all the parts are accessible to be readily cleaned. The stem 35 19 may be removed from its position in the mouth piece by first partially rotating it so as to cause the projection 24 to move out from the branch 26 and then the parts may be moved longitudinally, with the projection 24 passing 40 through the groove 25.

While I have illustrated and described the preferred embodiment of my invention, it is to be understood that I do not limit myself to the precise construction herein disclosed and the 45 right is reserved to all changes and modifications coming within the scope of the invention as defined in the appended claims.

Having thus described my invention, what I claim as new, and desired to secure by United 50 States Letters Patent is:

1. In a pipe, a hollow stem, a mouth piece with a reduced end engaging into the end of said stem, a bushing in the base of said hollow stem, a tube within the hollow of said stem and having its rear end threadedly engaging said bushing and connecting with a passage to the bowl of the pipe, a cup-shaped member engaging over said stem and having a rear stem engaging into the inner end of the mouth piece and having a slot alignable with a slot in the reduced end of said mouth piece forming a continuous passage for the smoke from the hollow of the stem through the mouth piece.

2. In a pipe, a hollow stem, a mouth piece with a reduced end engaging into the end of said stem, a tube in the hollow of said stem and having its inner end threadedly engaging into the base of said hollow and connecting with a passage to said bowl, and a cup-shaped member engaging over said tube and having a rear stem engaging into said mouthpiece, said stem being formed with a slot alignable with a slot in the reduced end of the mouth piece forming a continuous passage for the smoke from the hollow of the stem through the mouth piece.

3. In a pipe, a hollow stem, a mouth piece with a reduced end engaging into the end of said stem, a tube in the hollow of said stem and having its inner end threadedly engaging into the base of said hollow and connecting with a passage to said bowl, and a cup-shaped member engaging over said tube and having a rear stem engaging into said mouth piece, said stem being formed with a slot alignable with a slot in the reduced end of the mouth piece forming a continuous passage for the smoke from the hollow of the stem through the mouth piece, the reduced end of said mouth piece being frictionally engaged into the end of the hollow stem. 80

4. In a pipe, a hollow stem, a mouth piece with a reduced end engaging into the end of said stem, a tube in the hollow of said stem and having its inner end threadedly engaging into the base of said hollow and connecting with a passage to said bowl, and a cup-shaped member engaging over said tube and having a rear stem engaging into said mouth piece, said stem being formed with a slot alignable with a slot in the reduced end of the mouth piece forming a continuous passage for the smoke from the hollow of the stem through the mouth piece, the front end of said tube being formed with flattened sides, and said slotted stem being engaged upon said flattened sides to act as a turning tool for the stem so that it may be readily engaged and removed from place. 90

5. In a pipe, a hollow stem, a mouth piece with a reduced end engaging into the end of said stem, a tube in the hollow of said stem and having its inner end threadedly engaging into the base of said hollow and connecting with a passage to said bowl, and a cup-shaped member engaging over said tube and having a rear stem engaging into said mouth piece, said stem being formed with a slot alignable with a slot in the reduced end of the mouth piece forming a continuous passage for the smoke from the hollow of the stem through the mouth piece, the slot in the mouth piece extending inwards from the inner end of the mouth piece and communicating with the side of the slot in said stem. 100

6. In a pipe, a hollow stem, a mouth piece with a reduced end engaging into the end of said stem, a bushing in the base of said hollow stem, a tube within the hollow of said stem and having its rear end threadedly engaging said bushing and connecting with a passage to the bowl of the pipe, a cup-shaped member engaging over said stem and having a rear stem engaging into the inner end of the mouth piece and having a slot alignable with a slot in the reduced end of said mouth piece forming a continuous passage for the smoke from the hollow of the stem through the mouth piece, and means for holding said stem in various longitudinal adjusted positions upon said mouth piece so as to vary the passage for the smoke. 110

7. In a pipe, a hollow stem, a mouth piece with a reduced end engaging into the end of said stem, a bushing in the base of said hollow stem, a tube within the hollow of said stem and having its rear end threadedly engaging said bushing and connecting with a passage to the bowl of the pipe, a cup-shaped member engaging over said stem and having a rear stem engaging into the inner end of the mouth piece and having a slot alignable with a slot in the reduced end of said mouth piece forming a continuous passage for the smoke from the hollow of the stem through the mouth piece, and means for holding said stem in various longitudinal adjusted positions upon said mouth piece so as to vary the passage for the smoke, comprising 120

ing a projection on the end of the stem and the side thereof engaging into a longitudinal groove formed upon the inner wall of the mouth piece and engaging one of a plurality of transverse branches connecting with said longitudinal groove.	necting with a passage to the bowl of the pipe, and a cup-shaped member engaging over said stem and having a rear stem engaging into the inner end of the mouth piece and having a slot alignable with a slot in the reduced end of said mouth piece forming a continuous passage for the smoke from the hollow of the stem through the mouth piece, said bushing being threadedly engaged into the base of the hollow of said stem.	80
8. In a pipe, a hollow stem, a mouth piece with a reduced end engaging into the end of said stem, a bushing in the base of said hollow stem, a tube within the hollow of said stem and having its rear end threadedly engaging said bushing and con-	JOSEPH SZILAGYI.	85
